CLAIM

The ornamental design for a sensor bin, as shown and described.

DESCRIPTION

FIG. 1 is a perspective view of a sensor bin, showing my new design.

FIG. 2 is a top plan view thereof.

FIG. 3 is a front elevation view thereof.

FIG. 4 is a right-side elevation view thereof.

FIG. 5 is a rear elevation view thereof.

FIG. 6 is a bottom plan view thereof; and,

FIG. 7 is a left-side elevation view thereof.

The broken lines shown in the drawings represent portions of the sensor bin that are for illustrative purposes only and do not form a part of the claimed design.
